UNITED STATES PATENT OFFICE.

JAMES A. MCQUARRIE, OF JOGGIN MINES, NOVA SCOTIA, CANADA.

COMBINED COAT AND VEST.

1,271,047.

Specification of Letters Patent.

Patented July 2, 1918.

Application filed May 18, 1917. Serial No. 169,504.

To all whom it may concern:

Be it known that I, JAMES A. MCQUARRIE, a subject of the King of Great Britain, residing at Joggin Mines, in the Province of

5 Nova Scotia and Dominion of Canada, have invented new and useful Improvements in Combined Coats and Vests, of which the following is a specification.

This invention relates to combined coats 10 and vests and the object is to provide a plurality of members constituting the front portion of a vest, and means for attaching said members to a coat in such a manner that the vest members shall be in position 15 for use permitting them to be buttoned in the usual manner, and when it is desired to wear the coat as a one-piece garment, these vest members may be moved to a position under the facings of the coat and properly 20 secured.

A further object is to provide novel means for securing the vest members in either of the positions named.

In the drawings:

25 Figure 1 is a view showing the inner side of the coat, the outer side of one of the vest members and the inner side of the other of said members; Fig. 2 is a view showing the inner side of the coat with the vest members folded under the front facings of the coat; Fig. 3 is a view showing the facing of the coat turned outwardly and the position of the fastening devices thereon, the vest member being detached at its upper 30 portion; Fig. 4 shows one of the vest members with the fastening devices on the outer side thereof adjacent the edge and the arm hole; Fig. 5 is a section on the line 5—5 of Fig. 2.

40 This garment is designed for use as a portion of a summer suit and is intended to facilitate a change from the two-piece to a three-piece suit under circumstances which render such change desirable or when either 45 form would be more comfortable for the wearer.

The coat as a whole may be of substantially the usual design except that the facings are unattached at their upper ends except by the use of the temporary attaching means herein described. The temporary attaching means used along the edges of the facing and on certain portions of the vest members comprise snap catches 50 of ordinary construction, suitable sizes being selected in order that the members may

not project through the layers of cloth to the discomfort of the wearer or in such manner that an unsightly appearance will be 60 presented.

The facings are designated 10 and their free upper edges are shown at 12, the undersides of these upper edges being provided with fasteners 14 and 15 positioned to engage corresponding fasteners 16 and 17 secured to the inner portion of the coat proper. Additional fastening devices 18 and 19 are provided on the front portions of the facings at points slightly removed from their upper ends and the fastening devices last 70 mentioned serve to engage fasteners 20 and 21 on the upper ends of vest members 22 and 23. These vest members are also provided with fasteners 24 positioned to engage fasteners 25 on the inner sides of the facings 75 when the vest members are positioned between the facings and the coat proper. Fasteners are also provided along the lower edges of the vest members on their inner sides as shown at 26 and engage the complementary fasteners 27 on the inner sides 80 of the facings.

It is obvious that the particular location of the fastening devices has no bearing upon the invention considered broadly. 85

Short strips or tabs are or may be secured to the inner side of the coat at a point adjacent to the shoulder seam and are designated 30 and 31, being provided with fasteners 32 and 33 for engaging the fasteners 20, 21 at the upper edges of the vest members. When the garment is being worn as a one-piece garment the vest members are secured to the short strips or tabs above mentioned and the facings are folded 90 over the outer edges of the vest members and secured at their upper ends by means of the fasteners specified.

When the garment is being worn as a two-piece garment the vest members are folded 100 inwardly and are secured to the fasteners 18, 19 on the upper portions of the facing members next to the wearer.

It will be observed that I have provided a two-piece garment in which the vest members are secured in either of the positions specified without the addition of any members to the garment other than those usually employed in the design thereof. 105

What is claimed, is:—

1. In a garment, a coat having a facing extending inwardly from each of the front

edges thereof, said facings having unattached upper ends, detachable means for temporarily securing said upper ends, a plurality of vest members secured to the coat 5 along lines extending downwardly from the arm holes, detachable means for securing the upper ends of the vest members to the facing near the top thereof, and on that side of the facing next to the wearer and detachable 10 means for securing said upper ends at times between the facing and coat proper.

2. In a garment, a coat having a facing extending inwardly from each of the front edges thereof, said facings having unattached upper ends, detachable means for temporarily securing said upper ends to the coat proper along a line extending from the collar to each arm hole, a plurality of vest members secured to the coat along lines extending downwardly from the arm holes, detachable means for securing the upper 15 ends of the vest members to the facings near the top thereof and on that side of the fac- 20

ings next to the wearer at points adjacent to the collar, and detachable means for securing said upper ends at times between the facing and the coat proper along a line adjacent to the shoulder seam of the coat. 25

3. In a garment, a coat having a facing extending inwardly from each of the front edges thereof, said facings having unattached upper ends, detachable means for temporarily securing said upper ends, a plurality of tabs secured to the coat adjacent to the detachable means, a plurality of vest 30 members secured to the coat along lines extending downwardly from the arm-holes, detachable means for securing the upper ends of the vest members to the facings near the top thereof, and detachable means for 35 securing said upper ends of the vest members at times between the facing and the coat proper and to the aforesaid tabs. 40

In testimony whereof I affix my signature.

JAMES A. McQUARRIE.
